FIREARM

Edward E. Garland, Belleville, N. J.

Application March 28, 1941, Serial No. 385,611

4 Claims.

(Cl. 42—69)

This invention relates to firearms and particularly to the firing mechanism of semi-automatic firearms.

The operation of extraction, ejection, and reloading in autoloading firearms is so rapid that it would usually be impossible for the shooter to remove pressure from the trigger sufficiently rapidly to prevent the firing of two or more shots for each pull of the trigger. To overcome this difficulty various means have been proposed heretofore. Among these are the Y-type of trigger sear disclosed for example in the J. M. Browning Patent 659,507, issued October 9, 1900. One of the difficulties with said Browning construction is that the hammer is forced back so rapidly that it forces the trigger forwardly very rapidly, resulting in a stinging sensation which causes the finger to become sore after a certain number of shots have been fired and the sensation of pain connected with shooting causes the shooter to flinch, which results in the making of poor scores.

It is an object of the present invention to provide means which require that the trigger be released after the firing of a shot and again pulled before another shot can be fired, which means are so arranged that the re-cocking of the hammer cannot cause the trigger to impart a blow upon the finger of the shooter.

Another object is to provide such a device adapted for use in a gun wherein the trigger is located some distance to the rear of the hammer to permit the construction of such an arm having pleasing lines and balance.

Another object is to improve the construction shown in applicant's Patent 2,189,202, issued February 6, 1940, which comprises an improvement upon said Browning Patent 659,507 and illustrates a means whereby the lines of the gun may be improved by rounding the grip portion of the stock and moving the trigger rearwardly retaining the original position of the hammer and sear.

It is another object to provide a trip-off connection between a hammer and a sear so constructed that movement of the trigger will move the sear sufficiently far to disengage the hammer or other impact firing mechanism but wherein further movement of the trigger will result in a disconnection of the connecting means between trigger and the sear so that the sear may return to its normal hammer arresting position.

A more specific object is to provide such a trip-off arrangement in a firearm in which the trigger is located well rearwardly of the hammer,

including connections from the rearwardly placed trigger to the sear adjacent the forwardly placed hammer.

Other objects will appear from the following description of an illustrative embodiment of the invention taken together with the attached drawings wherein:

Fig. 1 is a side elevational view of a firearm embodying my invention, a part of the receiver and stock being shown in cross-section, the hammer, sear, and trigger being in position for firing;

Fig. 2 is a view showing certain of the parts of Fig. 1, the trigger having been pulled just sufficiently far to release the hammer; and

Fig. 3 is a view similar to Fig. 2, the trigger having been retracted further so as to trip the connection between the trigger and the sear permitting the return of the sear to a position where it may engage and arrest the hammer upon its return to its rearward position.

In said figures, the numeral 11 indicates generally the receiver of a firearm having a stock 12 secured thereto. 13 designates a trigger plate which is preferably made separate from the receiver proper but is fastened thereto and possibly also to the stock. Said trigger plate is shown as having pivoted thereto the hammer 14 at the pivot point 14a, said hammer being provided with a downwardly extending hook 14b cooperating with the hook 15b of a sear 15 pivoted at 15a to the trigger plate. A suitable sear spring such as 16 is provided to bias the sear clockwise as viewed in the drawing.

17 indicates a trigger pivoted at 17a to the trigger plate and having an upwardly extending portion 17b to which is pivoted at 17c a pawl 18 which is biased in a counterclockwise direction by means of a suitable spring such as the spring 19 shown.

Pivoted upon a cross bolt or other suitable pivot 20 is a roller 21 to which is pivoted at 21a a link 22 pivoted at 22a to the sear 15. Said roller 21 is formed with a shoulder 21b against which the pawl 18 may bear. It is also provided with a camming shoulder 21c just rearwardly of the shoulder 21b.

The hammer is normally biased forwardly by means of any suitable spring such as the leaf spring 22 fulcrumed at 23 and boosted in its action by means of plunger 24 operated by the powerful coil spring 24a. The spring 22 preferably acts upon the hammer 14 through a roller 14c.

In the parts shown in Fig. 1 it will be noted that the hammer spring strongly biases the ham-

mer towards firing position but that its movement is arrested by hook 15b on the sear. Furthermore, pawl 18 is in position behind the shoulder 21b and due to the pressure of spring 19, pawl 18 is pressed upon the roller 21 and the trigger has been moved clockwise to the limit of its motion. It will be seen therefore that the single spring 19 performs two functions, that of trigger spring and a spring to hold the pawl 18 downwardly.

If now the trigger 17 is pulled the pawl 18 will press against the shoulder 21b, rock the roller 21 counterclockwise, move link 22 to the left, rock sear 15 counterclockwise, releasing the hammer. The parts will now be in the position shown in Fig. 2, it being noted that the hammer is free to begin its excursion to the firing position. At this time the pawl 18 is still in engagement with the shoulder 21b but the shoulder 21c on the roller 21 is in position to lift the link 18. Further movement of the trigger is unavoidable due to the release of the friction which the thrust of the hammer spring had formerly applied to the hook 15b of the sear. The slightest further movement will cause the pawl 18 to be rocked sufficiently far so that shoulder 21c has cammed it off the shoulder 21b. When this occurs roller 21 turns clockwise under the impetus of sear 16 working through link 22.

During this time the sear has also rocked clockwise, presenting its hook 15b in position to engage the hook 14b of the hammer 14 upon the return of the hammer by the autoloading mechanism of the arm. The hammer is therefore arrested and cannot spring forward to fire the next cartridge.

In order to fire another cartridge it is necessary for the shooter to first release pressure upon the trigger 17 so that the pawl 18 may drop down into position behind the shoulder 21b. The parts have therefore resumed the position shown in Fig. 1 and are ready for the firing of the next shot.

It will be noted that the construction shown and described will serve admirably to accomplish the objects stated above. It is to be understood, however, that the construction disclosed above is intended merely as illustrative of the invention and not as limiting as various modifications therein may be made without departing from the invention as defined by a proper interpretation of the claims which follow.

I claim:

1. In an autoloading firearm, spring loaded impact firing means, a sear for normally arresting said firing means, a sear biasing spring, a trigger, a trigger biasing spring for biasing the trigger to normal position, connection means between said trigger and sear comprising a pawl pivoted on the trigger and a second pivoted member cooperating therewith and having a shoulder and a camming projection with which the trigger actuated pawl co-acts, the above-mentioned elements being so constructed and arranged that the trigger will first move the second pivoted member and thereby the sear to impact firing means releasing position and further movement of the trigger will cause the camming projection on the second pivoted member to disengage the pawl from the shoulder on the second pivoted member and thereby serve to break the connection between the trigger and the sear

so that the sear may return to its normal position to retain the impact firing mechanism upon the return of the latter to original position.

2. In an autoloading firearm, spring loaded impact firing means, a sear for normally arresting said firing means, a trigger located well rearwardly of the sear and provided with a forwardly extending pawl pivoted to the trigger, a pivoted intermediate member formed with an abutment shoulder adjacent the end of said pawl and a camming projection underlying said pawl, and a connecting link between said intermediate member and said sear, the above-mentioned elements being so constructed and arranged that movement of the trigger will first cause said pawl to move the intermediate member and there-through the sear to impact firing means releasing position and upon further movement of the trigger said camming projection will lift the pawl above said shoulder and serve to break the connection between the trigger and the sear so that the sear may return to its normal position to retain the impact firing mechanism upon the return of the latter to original position.

3. In an autoloading firearm, spring loaded impact firing means, a sear for normally arresting said firing means, a trigger located well rearwardly of the sear and provided with a forwardly extending pawl pivoted to the trigger, a spring for biasing said pawl downwardly, a pivoted intermediate member formed with an abutment shoulder adjacent the end of said pawl and a camming projection underlying said pawl, and a connecting link between said intermediate member and said sear, the above-mentioned elements being so constructed and arranged that movement of the trigger will cause said pawl to first move the intermediate member and there-through the sear to impact firing means releasing position and upon further movement of the trigger said camming projection will lift the pawl above said shoulder and serve to break the connection between the trigger and the sear so that the sear may return to its normal position to retain the impact firing mechanism upon the return of the latter to original position, and upon release of the trigger said trigger pawl spring will return the trigger to normal position with said link in position adjacent said abutment.

4. In an autoloading firearm, spring loaded impact firing means, a sear for normally arresting said firing means, a trigger located rearwardly of the sear and provided with a forwardly extending pawl pivoted to the trigger, a spring biasing said pawl downwardly, a sear operating member formed with an abutment shoulder adjacent the end of said pawl and a camming projection underlying said pawl, the above-mentioned elements being so constructed and arranged that movement of the trigger will first move the sear to impact firing means releasing position and upon further movement of the trigger said camming projection will lift the pawl above said shoulder and serve to break the connection between the trigger and the sear so that the sear may return to its normal position to retain the impact firing mechanism upon its return to original position, and upon release of the trigger said trigger pawl spring will return the trigger to normal position with said pawl in position adjacent said abutment.

EDWARD E. GARLAND.
